Primary Examiner — Mark A Goodwin(74) *Attorney, Agent, or Firm* — JCIPRNET(57) **CLAIM**

The ornamental design for an excavator, as shown and described.

DESCRIPTION

FIG. 1 is a rear, right, and top perspective view of an excavator showing our new design;

FIG. 2 is a rear, left, and top perspective view of FIG. 1;

FIG. 3 is a front view of FIG. 1;

FIG. 4 is a rear view of FIG. 1;

FIG. 5 is a left side view of FIG. 1;

FIG. 6 is a right side view of FIG. 1; and,

FIG. 7 is a top view of FIG. 1.

1 Claim, 7 Drawing Sheets(56)
